UNITED STATES PATENT OFFICE.

JAMES ANDERSON, JR., OF OMAHA, NEBRASKA.

DIRECTION-SIGNAL FOR MOTOR-VEHICLES.

1,246,375.

Specification of Letters Patent. Patented Nov. 13, 1917.

Application filed May 10, 1916. Serial No. 96,661.

To all whom it may concern:

Be it known that I, JAMES ANDERSON, Jr., a citizen of the United States, residing at Omaha, in the county of Douglas and State 5 of Nebraska, have invented certain new and useful Improvements in Direction-Signals for Motor-Vehicles, of which the following is a specification.

My invention relates to new and useful 10 improvements in direction signals and more particularly direction signals for motor vehicles, the primary object of my invention being the provision of a signal device which may be attached to the front or rear of a 15 vehicle and which may be operated to indicate the intention of the driver of the vehicle to turn to the right or left. As a rule, one of the signaling devices will be located at each end of the vehicle and each device 20 is so arranged that it may indicate which direction the vehicle is to turn.

A still further object of my invention consists in constructing a signaling device which, in effect, is in the outline of a pair 25 of arrows pointing in opposite directions with their shafts overlapping, being disposed one above the other, with the end of each shaft abutting against the head of the other shaft to economize in space and provide a compact structure.

A still further object of my invention is to so partition off the body that each arrow 30 constitutes a chamber separate and distinct from the chamber of the other and in providing a signal light in each of the chambers.

In this connection, a still further object 35 of my invention is to provide the body of the device with a face plate having translucent panels outlining the arrows, the panels being preferably formed of colored glass and so arranged that the heads of the arrows will appear red and the shafts blue when the signal is illuminated.

A further object of my invention 40 consists in the provision of a novel arrangement for properly partitioning off the shaft portions of the body to provide the chambers above mentioned.

With these and other objects in view, my 45 invention will be more fully described, illustrated in the accompanying drawings, and then specifically pointed out in the claims which are attached to and form a part of 50 this application.

In the drawings:

Figure 1 is a perspective view of my improved signal device;

Fig. 2 is a corresponding view with the 60 face of the device removed;

Fig. 3 is a central longitudinal sectional view, a portion of the partition wall being broken away;

Fig. 4 is a central vertical sectional view;

Fig. 5 is a diagrammatic view, illustrating 65 one method of wiring a vehicle equipped with my signals.

Corresponding and like parts are referred to in the following description and indicated in all the views of the drawings 70 by the same reference characters.

The body portion 10 of my improved signal device includes a base 11 surrounded by a marginal wall 12, the base and, consequently, its marginal wall being so shaped 75 as to provide an open faced body having a rectangular intermediate portion and slightly offset triangular end portions, one end portion being offset upwardly and the other correspondingly offset downwardly in 80 the manner clearly shown in Figs. 1 and 2. The intermediate portion of the base, along its edges, is provided with flanges 13 having openings 14 through which screws, bolts or other fastening means may be passed to secure the body either directly to the vehicle 85 or to suitable brackets carried by the vehicle. This body may be constructed of wood, sheet metal or any other suitable material, sheet metal being preferred.

A longitudinal partition wall 15 extends throughout the length of the intermediate portion of the body and at its inner edge 90 is bifurcated and curved to form substantially semicylindrical back walls 16 engaging against the base, as best shown in Fig. 4, and engaging at their free edges against the upper and lower marginal walls. By means of this partition wall, in connection with the intermediate portions of the 95 marginal walls, I define what may be termed shaft portions 17 and 18 for the arrow heads 19 and 20, respectively, and it will be seen that the portions of the marginal walls defining the arrow heads 19 and 20 serve to close the shaft portions at one end. That is, a portion of the marginal wall of the head 19 closes the free end of the shaft portion of the head 20, while a portion of the marginal wall of the head 20 closes the free end of 100 110

the shaft portion 17 of the arrow head 19. By this means, two arrow shaped chambers are provided in which the arrows point in opposite directions and the shaft portions of which overlap and these chambers may be illuminated by electric light bulbs 21 and 22 mounted in the arrow head portions of the chambers. The light bulbs are mounted in suitable sockets 23 secured to the base 10 of the body and the electric light wires are run into the body through an opening 24 formed in the base and along the space between the base and the branch portions of the partition wall 15 and so through suitable openings 25 formed in the marginal walls of the arrow heads and into the heads of the arrows and into the light sockets. Because of this, there is absolutely no communication between the arrow shaped chambers and the illumination of either chamber will not illuminate the other.

The above described body is closed by a face plate or closure 26 corresponding in outline to the outline of the body and having a marginal flange 27 fitting about the marginal wall of the body and provided at suitable intervals with eyes 28 to receive the bills of hooks 29 swingingly mounted upon the marginal wall of the body, where- 30 by the closure is secured to the body. This closure in effect is merely a frame, its marginal flange 27 being split at suitable intervals and bent inwardly to provide glass retaining flanges or strips 28' and the flange 35 27 in spaced relation to these strips is looped inwardly to provide a marginal shoulder 29' in order that suitably shaped pieces of glass may be seated and anchored between the shoulders or seats 29' and the strips 28'. 40 Pieces of glass 30 are mounted in the arrow head portions of this frame and pieces of glass 31 are mounted in the shaft portions, the intermediate portion of the frame being formed with a medial brace strip 32 45 extending parallel to the partition wall 15. The glass covering the arrow head portions of the device is preferably red, while that covering the shaft portions is preferably of some other distinctive color, such as blue. 50 Obviously, if current is supplied to the light 21, the glass face of the arrow head 19 will be illuminated and will appear bright red, while the glass face of the shaft 17 will be correspondingly illuminated, showing 55 bright blue. The signal will, therefore, present the appearance of an arrow pointing to the right and having a red head and blue shaft. In like manner, if current is supplied to the light 22, the other arrow 60 will be illuminated.

Obviously, there are many ways in which a vehicle may be wired when my signal devices are employed but for the sake of clearness I have illustrated one simple 65 method in Fig. 5. In this figure I have as-

sumed that two signaling devices are employed, one at A at the front portion of the vehicle, and one at B at the rear portion, the light bulbs being indicated by their respective numerals 21 and 22, it of course being apparent that if the light bulb 21 is at the right upon the rear signal it will be at the left upon the forward signal, looking at the signals from the rear and front of the vehicle, respectively, as they would appear to pedestrians or drivers of other vehicles. A wire 33 connects one contact of the light socket 21 at the front signal with the contact of the light socket 22 at the rear signal, while a wire 34 connects contacts of the other light sockets. A wire 36 connects the other contacts of the two rear light sockets and wires 37 and 38 connect the free contacts of the two front sockets, respectively, to the fixed contacts 39 and 40 of a two-way switch 41 having the swinging contact or switch blade 42. A wire 43 leads from this switch blade to a battery 44 or other suitable source of electrical energy and a wire 45 leads from the other pole of this battery to the wire 36.

It will, of course, be clear that if the switch blade 43 is swung to the left to engage the contact 39, the circuit will be closed, including the battery, the light 21 at the front signal and the light 22 at the rear signal. If, on the other hand, the switch blade is swung in the opposite direction, the circuit will be closed, including the battery, the light 22 at the front signal and the light 21 at the rear signal.

Having thus described the invention, what is claimed as new is:

1. A direction indicator including a base surrounded by a marginal wall defining and forming an open faced casing in the shape of a pair of oppositely directed arrows, the shafts of which overlap, the shaft of one arrow abutting against the head of the other arrow, a longitudinal partition abutting at its ends against the heads of the arrows and separating and defining the shafts thereof, said partition at its inner end being bifurcated and oppositely curved to provide reflecting back walls within the casing which constitute the back walls of the shaft portions, electric light bulbs mounted in the head portions of the arrows, and a closure for the casing having non-opaque portions defining and overlying the arrows.

2. A direction indicator including a base surrounded by a marginal wall defining and forming an open faced casing in the shape of a pair of oppositely directed arrows, the shafts of which overlap, the shaft of one arrow abutting against the head of the other arrow, a longitudinal partition abutting at its ends against the heads of the arrows and separating and defining the shafts thereof, said partition at its inner end being bifur-

cated and oppositely curved to provide reflecting back walls within the casing which constitute the back walls of the shaft portions, electric light bulbs mounted in the 5 head portions of the arrows, and a closure for the casing having non-opaque portions defining and overlying the arrows, said closure including a marginal portion adapted to encircle the marginal wall of the 10 casing and folded inwardly upon itself throughout its length to provide a seat to receive glass panels, the marginal portion having its free edge inbent to provide retaining flanges to engage against glass 15 panels positioned against the seats, and glass panels retained between the seats and flanges.

3. A direction indicator including a base and walls defining an open faced casing, a 20 signal light mounted in the casing, and a closure for the casing including a marginal portion adapted to engage against the outer faces of the walls of the casing and folded inwardly upon itself throughout its length 25 to provide a seat to receive glass panels, the marginal portion having its free edge inbent to provide retaining flanges to engage against glass panels positioned against the seats, and glass panels retained between the 30 seats and flanges.

4. A direction indicator including a back

wall, forwardly projecting wall portions defining a pair of oppositely directed spaced arrow head shaped chambers, the axes of which are horizontally disposed at slightly 35 different levels and the adjacent sides of which are formed with axial openings, a partition wall projecting forwardly and extending from one side at the opening of one chamber to the other side of the opening of 40 the other chamber, additional forwardly projecting wall portions parallel to and spaced at each side of the partition wall and extending from chamber to chamber to define with the partition wall overlapping arrow shaft forming chambers, each communicating at one end with one arrow head 45 shaped chamber through the opening therein and being closed at its opposite end by the wall of the other arrow head shaped chamber, a closure engaging against the forward edges of the walls and having arrow shaped inserts of non-opaque material coincident with the head and shaft shaped chambers of the arrows, and signal lights disposed within the arrow head shaped chambers, whereby each arrow head shaped chamber and its shaft shaped chamber may be illumined independently of the other.

In testimony whereof I affix my signature. 50

JAMES ANDERSON, JR. [L.s.]
